UNITED STATES PATENT OFFICE.

LUTHER D. LOVEKIN, OF PHILADELPHIA, PENNSYLVANIA.

FEED-WATER HEATER.

1,287,713.

Specification of Letters Patent. Patented Dec. 17, 1918.

Application filed September 25, 1916. Serial No. 122,015.

To all whom it may concern:

Be it known that I, LUTHER D. LOVEKIN, a citizen of the United States of America, and a resident of the city and county of 5 Philadelphia, State of Pennsylvania, have invented a certain new and useful Improvement in Feed-Water Heaters, of which the following is a true and exact description, reference being had to the accompanying 10 drawings, which form a part thereof.

My present invention relates to heat interchanging apparatus of the surface condenser type in which heat is transferred to a colder fluid flowing through a group of 15 spaced apart tubes from a condensable vapor, as steam, in contact with the outer walls of the tubes, and the general object of the invention is to provide simple and effective apparatus of the type characterized 20 by its efficiency and relatively high capacity per unit of bulk. More specifically the object of my invention is to provide improved means for preventing liquid of condensation forming on and dripping off upper tubes 25 from running over the lower tubes and thereby through the heat insulating effect of the liquid reducing the coefficient of heat transmission through the tube walls.

The various features of novelty which 30 characterize my invention are pointed out with particularity in the claims annexed to and forming a part of this specification. For a better understanding of the invention, however, and the advantages possessed by 35 it, reference should be had to the accompanying drawings and descriptive matter in which I have illustrated and described a preferred embodiment of my invention.

Of the drawings:

40 Figure 1 is a sectional elevation of a preferred embodiment of my invention;

Fig. 2 is a section taken on the line 2—2 of Fig. 1; and

45 Fig. 3 is a section taken similarly to Fig. 1 but on a larger scale and showing a portion only of the apparatus.

In the drawings, A represents the casing body of apparatus of the surface condenser type especially devised for use on and as 50 a part of a locomotive for heating the feed water for the locomotive with the exhaust steam from the locomotive. To the ends of the casing body A are secured chambered end members B and C. As shown, the end 55 member C is directly secured by bolts K to the adjacent end of the casing body A,

the corresponding tube sheet D being clamped at its margin between the casing body and the end member C. The end member B is connected by bolts K to the adjacent 60 tube sheet D which, with the end member B, is connected to the adjacent end of the casing body A by the flexible casing portion F which forms an expandable joint to take care of the relative expansion of the casing 65 body A and the tubes E which are rigidly connected at their ends in the tube sheets D. The tubes E are approximately horizontally disposed. As shown, the steam space within the casing body A traversed by the tubes 70 E is provided with two steam inlets A' at its upper edge and a bottom outlet A² for water of condensation. The end member B is formed with an inlet chamber B' and an outlet chamber B² for the feed water 75 passing through the apparatus. The feed water to be heated entering the chamber B' passes through the tubes E opening to that chamber to the chamber in the end member C and returns from that chamber to the 80 chamber B² through the tubes E opening to both of said chambers. It will be understood, however, that it is immaterial to the present invention whether the chambered end members be provided with external connections to insure one or any desirable plurality of passages of the water being heated from one end of the apparatus to the other.

Surrounding each tube E and anchored at its ends to the corresponding tube sheets is 90 a casing tube or jacket G substantially larger in internal diameter than the external diameter of the tube E which it surrounds, and which will ordinarily be concentrically disposed therein. Each tubular jacket G is 95 formed with one or more steam inlets in its upper edge and one or more outlets for water of condensation in its lower edge, and these inlets and outlets are so relatively arranged that the water of condensation escaping 100 from a water of condensation outlet of any upper jacket G will not enter the steam inlet of any lower jacket. In the preferred construction illustrated each tube G is formed with a steam inlet G' in its upper edge in 105 the shape of an elongated slot terminating at each end at a short distance from the corresponding tube sheet, and is formed adjacent each end, with a bottom discharge opening G². The outlets G² adjacent each tube sheet 110 lie between the latter and the adjacent ends of the slots G'. Of course, if the tubes and

jackets are inclined to the horizontal, there is no necessity for the outlets G^2 at the upper ends of the jackets G . Advantageously the tubular jackets G are held in place by counterboring the tube sheets to form sockets D' in which the ends of the jackets are inserted.

In the operation of the apparatus illustrated, the steam enters the interiors of the various jackets G through the slots G' , and thus contacts with the active tubes E . The water of condensation forming on the outer walls of the tubes E and in the annular spaces between the tubes E and their surrounding casing jackets G , is collected in the tubes G and flows out of the latter through the discharge openings G^2 . The water escaping from any outlet G^2 of an upper jacket falls onto and runs over the ends of the jackets G beneath, but the staggered arrangement of the inlets and outlets prevents any appreciable portion of this water from entering the inlets G' of any of the lower jackets G . The jackets G thus form very simple and effective means for preventing the water of condensation formed on the outer wall, or in immediate proximity to any one tube E , from running over the wall of any other tube E and thereby reducing the effectiveness of the apparatus.

While in accordance with the provisions of the statutes I have illustrated and described the best form of my invention now known to me, it will be apparent to those skilled in the art that changes can be made in the form of my invention without departing from its spirit, and that some features of my invention can be used without a corresponding use of other features.

Having now described my invention, what I claim as new and desire to secure by Letters Patent, is:—

1. Heat exchange apparatus comprising a group of horizontally disposed tubes traversing a vapor space, and a separate tubular jacket for and embracing each of

said tubes but not filled by the latter, said jackets being formed with vapor inlets at their upper edges and liquid of condensation outlets at their lower edges, the inlets to and outlets from the various jackets being relatively disposed longitudinally of the tubes to prevent liquid of condensation escaping from the outlet of an upper jacket from entering the inlet of a lower jacket. 50

2. Heat exchange apparatus comprising 55 in combination a casing inclosing a vapor space, a group of horizontally disposed tubes traversing said vapor space, tube sheets to which the ends of the tubes are connected, and tubular jackets, one for and embracing but not filled by each of said tubes and each connected at its opposite ends to the tube sheets and formed with a vapor inlet at its upper edge and a liquid of condensation outlet at its lower edge, the inlets to and outlets from the various jackets being relatively disposed longitudinally of the tubes to prevent liquid of condensation escaping from the outlet of an upper jacket from entering the vapor inlet of a lower jacket. 65

3. Heat exchange apparatus comprising 70 in combination a casing inclosing a vapor space, a group of horizontally disposed tubes traversing said vapor space, tube sheets to which the ends of the tubes are connected, and tubular jackets, one for and embracing but not filled by each of said tubes, said tube sheets being formed with sockets receiving the ends of said jackets, and each of said jackets being formed with a vapor inlet at 75 its upper edge and a liquid of condensation outlet at its lower edge, the inlets to and outlets from the various jackets being relatively disposed longitudinally of the tubes to prevent liquid of condensation escaping from the outlet of an upper jacket from entering the vapor inlet of a lower jacket. 80

LUTHER D. LOVEKIN.

It is hereby certified that in Letters Patent No. 1,287,713, granted December 17, 1918, upon the application of Luther D. Lovekin, of Philadelphia, Pennsylvania, for an improvement in "Feed-Water Heaters," an error appears in the printed specification requiring correction as follows: In the heading, line 4, for "Serial No. 122,015" read *Serial No. 122,045*; and that the said Letters Patent should be read with this correction therein that the same may conform to the record of the case in the Patent Office.

Signed and sealed this 11th day of March, A. D., 1919.

[SEAL.]

R. F. WHITEHEAD,

Acting Commissioner of Patents.
